UNITED STATES PATENT OFFICE.

CHARLES W. DAKE, OF CHICAGO, ILLINOIS, ASSIGNOR TO PYLE-NATIONAL ELECTRIC HEADLIGHT COMPANY, OF CHICAGO, ILLINOIS, A CORPORATION OF NEW JERSEY.

ARC-LIGHT ELECTRODE.

1,112,361.

Specification of Letters Patent. Patented Sept. 29, 1914.

Application filed December 5, 1912. Serial No. 735,034.

To all whom it may concern.

Be it known that I, CHARLES W. DAKE, a citizen of the United States, residing at Chicago, in the county of Cook and State of Illinois, have invented a certain new and useful Improvement in Arc-Light Electrodes, of which the following is a specification.

My invention relates to electrodes for arc lamps and particularly to such as are intended to be used at a temperature close to the fusing point of such electrodes. A particular case is that where copper electrodes are employed in connection with or in opposition to other electrodes such as those of carbon. In this and many other cases it is desirable to have an electrode of such a nature that it will tend to radiate heat or so act as to keep its own temperature down. Such an electrode is the object of my invention. It is illustrated in the accompanying drawings, wherein—

Figure 1 is a vertical section showing two electrodes in opposition to each other; Fig. 2 is a plan view of the lower electrode and associated parts; Fig. 3 is a cross section on the line 3—3 of Fig. 1; and Fig. 4 is a side elevation of the electrode.

Like parts are indicated by the same letter in all the figures.

The electrode consists of a central core A with a series of laterally projecting longitudinal ribs B, B thereon. The total effect is that of a corrugated or ribbed electrode. The edges of the ribs are preferably notched at C, but this is only for convenience in the application of the electrode to that particular form of holder which is here illustrated but made the subject matter of another application, Serial Number 735,033, filed December 5, 1912, for an electrode holder for

arc lamps. These notches, however, have another purpose and for that purpose they are made as indicated, uniform in length, and are associated with a notched holder as shown. The electrode, although metallic, tends, of course, to gradually disintegrate or to become reduced in length at the point where the arc is established. Since these notches are of uniform length, they enable the adjustment of the electrode to accommodate for such wear by uniform increments. It is easy to determine by actual experience about how long it takes the electrode to wear the length of one notch, whereupon the practice can be established of moving the electrode forwardly one notch at the end of each such period of time. The grooves in the electrode, or the intervals between the ribs serve a further purpose in that they furnish a bearing for a removable locking portion of the holder. By this means the electrode with its projecting parts can be held by opposed projecting ribs or portions and the holding part prevents its rotation on its own axis.

I claim:

An electrode comprising a thin central metallic core symmetrically disposed cooling ribs longitudinally arranged said ribs extending throughout the entire length thereof uniform equidistant notches transversely arranged across the outer surface of said ribs.

In testimony whereof, I affix my signature in the presence of two witnesses this 3rd day of December, 1912.

CHARLES W. DAKE.
